UNITED STATES PATENT OFFICE.

STANLEY RONDA, OF TOLEDO, OHIO.

DESIGN FOR A CIGAR-HOLDER AND ASH-TRAY.

45,892.

Specification for Design.

Patented June 2, 1914.

Application filed March 14, 1914. Serial No. 824,827. Term of patent 7 years.

To all whom it may concern:

Be it known that I, STANLEY RONDA, a subject of the Emperor of Austria-Hungary, residing at Toledo, in the county of Lucas and State of Ohio, have invented a new, original, and ornamental Design for a Cigar-Holder and Ash-Tray, of which the following is a specification, reference being had to the accompanying drawing, forming part thereof.

The figure is a perspective view of a cigar holder and ash tray, showing my new design.

I claim:—

The ornamental design for a cigar holder and ash tray, as shown.

STANLEY RONDA.
